(57) **CLAIM**

The ornamental design for a back view hanging mirror, as shown and described.

DESCRIPTION

FIG. 1 is a front, mirror-folded perspective view of a first embodiment of a back view hanging mirror showing my design therefor;

FIG. 2 is a rear, mirror-folded perspective view thereof;

FIG. 3 is a front, mirror-folded elevational view thereof;

FIG. 4 is a rear, mirror-folded elevational view thereof;

FIG. 5 is a right, mirror-folded side elevational view thereof;

FIG. 6 is a left, mirror-folded side elevational view thereof;

FIG. 7 is a top, mirror-folded plan view thereof;

FIG. 8 is a bottom, mirror-folded plan view thereof;

FIG. 9 is a front, mirror-unfolded, perspective view thereof;

FIG. 10 is a rear, mirror-unfolded, perspective view thereof;

FIG. 11 is a front, mirror-unfolded elevational view thereof;

FIG. 12 is a rear, mirror-unfolded elevational view thereof;

FIG. 13 is a right, mirror-unfolded side elevational view thereof;

FIG. 14 is a left, mirror-unfolded side elevational view thereof;

FIG. 15 is a top, mirror-unfolded plan view thereof;

FIG. 16 is a bottom, mirror-unfolded plan view thereof;

FIG. 17 is a front, mirror-folded perspective view of a second embodiment of a back view hanging mirror showing my design therefor;

FIG. 18 is a rear, mirror-folded perspective view thereof;

FIG. 19 is a front, mirror-folded elevational view thereof;

FIG. 20 is a rear, mirror-folded elevational view thereof;

FIG. 21 is a right, mirror-folded side elevational view thereof;

FIG. 22 is a left, mirror-folded side elevational view thereof;

FIG. 23 is a top, mirror-folded plan view thereof;

FIG. 24 is a bottom, mirror-folded plan view thereof;

FIG. 25 is a front, mirror-unfolded perspective view thereof;

FIG. 26 is a rear, mirror-unfolded perspective view thereof;

FIG. 27 is a front, mirror-unfolded elevational view thereof;

FIG. 28 is a rear, mirror-unfolded elevational view thereof;

FIG. 29 is a right, mirror-unfolded side elevational view thereof;

FIG. 30 is a left, mirror-unfolded side elevational view thereof;

FIG. 31 is a top, mirror-unfolded plan view thereof; and,

FIG. 32 is a bottom, mirror-unfolded plan view thereof.
